UNITED STATES PATENT OFFICE.

CHARLES E. FULLER, OF OMAHA, NEBRASKA.

RAILWAY-CAR.

1,176,954.

Specification of Letters Patent. Patented Mar. 28, 1916.

Application filed October 11, 1915. Serial No. 55,248.

To all whom it may concern:

Be it known that I, CHARLES E. FULLER, a citizen of the United States, residing at Omaha, in the county of Douglas and State 5 of Nebraska, have invented a certain new and useful Improvement in Railway-Cars, of which the following is a specification.

This invention relates to railway cars and consists in a means applicable to all-steel 10 cars for supporting temporary floors or stringers at various different heights above the main floor of the car.

Many manufacturers of automobiles and similar machinery make a practice of shipping 15 their product two-high in box cars. This necessitates temporary cross stringers to carry the upper tier and in cars of wooden construction these can readily be applied.

It is the purpose of my invention to permit this practice with cars of steel construction without imposing any very close limitations upon the height or spacing of the 20 stringers, which are necessarily subject to variation to suit the loading. To accomplish this result I make use of a number of 25 pendant hanger bars which may be held either in an inoperative position beneath the roof of the car, or in an operative position 30 vertically against the side walls of the car.

In the latter position they are adapted to support at any chosen height, longitudinal 35 stringers or sills upon which may be placed and secured in any desired spacing the load-

supporting cross sills.

Certain details of construction of the hanger bars to adapt them to the needs of this construction are also features of my invention.

I illustrate the invention applied to an all-steel box car in the accompanying drawing, in which:—

Figure 1 is a transverse section of a car body showing the hangers lowered, and the 45 longitudinal stringers applied. The position of the transverse stringers is indicated in dotted lines; Fig. 2 is a similar view showing all stringers removed and the hangers swung up to inoperative position 50 against the roof; Fig. 3 is a perspective view of the hanger bar in lowered position, the hinge-bearing and latch pocket being broken away to show the construction; Fig. 4 is a perspective view of the latching end 55 of a hanger bar; and Figs. 5 and 6 are perspective views of retaining loops for the

hanger bars on opposite sides of the car, showing how these are offset to allow them to be carried by the same carline and yet permit overlapping of the opposite hangers. 60

In the drawings 11 represents the floor of the car, 12 is the side framing, 13 the sheathing, and 14 the carlines. The roof sheathing and the purlins are omitted. Such of the car structure as is shown is 65 purely illustrative and subject to variation.

Fastened at suitable intervals to the side walls of the car near the top, and preferably at such points as to receive support from the framing of the car are hanger brackets 70 15, each carrying a hinge pintle bolt 16.

Mounted on each hanger bracket by means of elongated loops or eyes 17 are the hanger bars 18 each of which terminates in a T-head 19. One arm of the T-head carries a 75 beveled latch-hook 20 to enter and latch in a pocket 21, the elongated loop, or eye 17 serving to permit the necessary vertical movement of the bar 18. The other arm of the T-head serves to support the longitudinal 80 stringer 22 either directly, or as here shown, through an interposed filler block 23. Bolts 24 passing through chosen ones of a series of bolt holes 25 are the preferred means for attaching the stringers 22 and 85 blocks 23.

The longitudinal stringers 22 serve to support cross stringers or any other suitable structure which may, if desired, be nailed 90 directly to them.

After removing the stringers 22 the bars 18 may be unlatched from the pockets 21 and swung up across the roof of the car where they are retained by loops 26 hinged to bracket plates 27. The plates 27 are carried 95 by the carlines 14 where possible and the loops 26 for the opposite bars 18 of each pair are offset sufficiently to permit the overlapping of the bars. The brackets 15 at opposite sides of the car may be offset or staggered or where this is not desirable the hinge joints may be made loose enough or so formed as to permit the bars to swing clear of each other.

The advantages of the construction are 100 that it may be applied to existing cars, has few working parts, offers a rigid support in all directions when in use, and is completely out of the way when not in use.

The bars 18 may be made of any desired 110 length practically up to the inside width of the car and may be provided if desired with

any number of bolt holes 25 through any desired range to permit the attachment of longitudinal stringers at corresponding heights.

Other variations will readily suggest themselves.

Having thus described my invention, what I claim is:—

1. The combination with a car body of a plurality of bars hingedly mounted within 10 the same to swing between an inoperative position near the car roof, and an operative vertical position adjacent the sides of the car; holding means for retaining said bars in said inoperative position; fastening means 15 for fixing them in operative position; and means for attaching a temporary structure to said bars.

2. The combination with a car body of a plurality of bars hingedly mounted within 20 the same to swing between an inoperative position near the car roof, and an operative

vertical position adjacent the sides of the car; holding means for retaining said bars in said inoperative position; fastening means for fixing them in operative position; and 25 adjustable attaching means for attaching a temporary structure to said bars at different heights above the car floor.

3. The combination with a car body of a hanger attached thereto; a supporting bar 30 provided with supporting means for a temporary structure; a pin-and-slot hinge-connection between said hanger and bar; a keeper carried by said car body; a latching head carried by said supporting bar and engageable with said keeper by the vertical shifting of said bar on said pin-and-slot connection; and means for retaining said bar in inoperative position when not in use.

In testimony whereof I have signed my 40 name to this specification.

CHARLES E. FULLER.
